UNITED STATES PATENT OFFICE.

HARVEY R. WOLFE, OF LOUISVILLE, KENTUCKY, ASSIGNOR TO CHARLES A. WOLFE, THOMAS BRENNAN, W. GARNETT MUNN, AND JOHN LEAMY, OF SAME PLACE.

SMOKE-CONSUMING FURNACE.

SPECIFICATION forming part of Letters Patent No. 272,930, dated February 27, 1883.

Application filed October 6, 1882. (No model.)

To all whom it may concern:

Be it known that I, HARVEY R. WOLFE, residing at Louisville, Jefferson county, Kentucky, have invented certain new and useful 5 Improvements in Smoke-Consuming Furnaces, of which the following is a full, clear, and exact description.

My invention relates to an improvement in smoke-consuming furnaces, in which steam is mingled with the products of combustion for the purpose of completing and perfecting combustion, increasing the heat, and consuming the smoke; and it consists, first, in the novel method of injecting the steam into the fire-chamber of the furnace; second, in the construction of a hollow grate-bar containing compartments for conveying and distributing the steam in the fire-chamber; third, the steam-boxes along the side of the chamber, in combination with 15 the grate-bar; fourth, an adjustable upright arm for conveying heated steam to the fire-chamber and throwing it upon the fire superheated and in any desired direction; fifth, the manner of supporting the adjustable arm and 20 operating it.

Figure 1 is an end view of furnace, partly in section. Fig. 2 is a plan view of the bottom of the fire-chamber, partly in section. Fig. 3 is a vertical section of the hollow grate-bar, 30 taken in a line parallel with the bar. Fig. 4 is a section of the adjustable arm. Fig. 5 is a cross-section of the same, showing the mechanism for operating it.

A is the fire-chamber, below which is the 35 ordinary ash-pit.

B is a boiler of any desired construction, and C a steam-dome on the boiler.

D D are the ordinary grate-bars, only partly shown. They extend the entire length of the 40 chamber, forming part of the bottom of the fire-chamber. Beside these ordinary grate-bars, there is an additional larger grate-bar, E, extending the entire length of the fire-chamber. This bar, which is shown in section in Fig. 3, is hollow and provided with several 45 chambers for conveying steam to the fire-chamber.

The chambers F, G, H, and I open through

the slots K K K in their top directly into the fire-chamber. These chambers are connected together by the openings m m. The chamber K, which is independent of the others, is connected with a hollow upright arm, X, which is pivoted to the grate-bar E, as shown at O in Figs. 4 and 5. The arm X is thus pivoted so as to be adjustable backward and forward, for the purpose hereinafter described, and the slot K', connecting the chamber K with the arm X, is segment-shaped, so as to be open and afford a free passage for the steam in whatever position the arm X may be. The lower end of the arm X is provided with the pivoted screw-bolt P, one end being pivoted to the upright arm X and the other passing through the front of the furnace, where it is adjusted by the nuts r r. As the lower end of the upright arm X is drawn forward, the top is thrown back, and vice versa.

S are steam-boxes arranged along the side of the fire-chamber, and provided with nozzles s s, through which steam is thrown into the fire-chamber, mingling with the products of combustion, or directly on the burning fuel in the fire-chamber. Steam is conveyed to the hollow grate-bar and the steam-boxes S S by 75 any convenient number of pipes T from the steam-dome C. The nozzles s s of the steam-boxes are so arranged that the jets of steam passing through them are thrown back in the general line of the draft, as indicated by the 80 dotted lines s' s'. Steam is admitted to the chamber F in the hollow grate-bar at F'. The slots at the top of the chambers F, G, H, and I are provided at the front end with an overhanging deflector, U, which throws the steam 85 backward and forms a current; and in order to make this current clear, openings v v v are made in the walls between the chambers, at the top, and slanting parallel with the deflectors U, so that the steam passes freely from 90 one chamber to another and out of these slots. The pressure of the steam keeps the slots K open. Steam is admitted to chamber K in the grate-bar E through the pipe W, and is conveyed through the slot K' into the upright arm 95 X. This arm is provided at the top with a hol-

low T-head, Z, extending across the fire-chamber; or any convenient form of distributor may be used. This T-head has either a horizontal slot, y, or small perforations for the passage of steam. As steam is forced through the pipe W into the chamber K and upright arm X, it is distributed upon the fire or into the products of combustion through the slot y or small perforations, as indicated by the dotted lines "y".

10 These jets of steam may be thrown down into the fire by shortening the bolt P and throwing the T-head back toward the rear of the fire-chamber. They may be thrown upward by lengthening the bolt P and bringing the T-head forward, or they may be thrown horizontally into the fire-chamber by adjusting the bolt P so that the arm X is perpendicular. The direction of these jets of steam may be regulated or changed at any time while the furnace is in operation by the bolt P.

15 Q Q are cocks for shutting off or regulating the steam.

20 The upright arm X may be located in any part of the fire-chamber most convenient, where it will be heated by the fire, but preferably as shown in the drawings. As it passes up into the fire-chamber it quickly becomes heated and heats the steam which passes through it, so that when the steam is ejected at y it will 25 be superheated to a high degree. I am aware that steam has been injected into the fire-chamber of a furnace from the walls, and I do not claim that; but the steam-boxes S S are set out in the fire-chamber, where they become somewhat heated, and the steam is thrown

30 from them hot and not mingled with air. It is also an important advantage to be able to adjust and alter the direction of the steam-jets thrown from the upright arm X. It is not necessary here to explain the effect of mingling 40 steam with the products of combustion, as they are well known, and I do not claim, broadly, the injection of steam into the fire-chamber of a furnace; but

45 I do claim as my invention—

1. In a furnace provided with means for distributing superheated steam at varying angles to the fire, the hollow grate-bar E, provided with the deflecting-chambers F, G, H, and I, and independent chamber K, substantially as 50 50 and for the purpose described.

2. The steam-conveying arm X, provided with a regulating and adjusting screw, P, and so pivoted as to extend up into the fire-chamber of the furnace at or near the front end, in combination with the grate of said furnace, substantially as described.

3. In a furnace, in combination, the hollow grate-bars, provided with deflecting-chambers and steam-connections for admitting steam to 60 the fire, and the adjustable arm X for admitting superheated steam at various angles of inclination, the steam-boxes S S for admitting steam at both sides of the furnace and at an angle to the fire, substantially as described.

HARVEY RUDY WOLFE.
